(57) CLAIM

The ornamental design for a home fragrance dispenser, as shown and described.

DESCRIPTION

FIG. 1 is a perspective view of a home fragrance dispenser according to our new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top plan view thereof shown in an illuminated state.

The dash-dot broken lines represent the boundaries of the claimed design and form no part of the claimed design. The broken lines outside of the boundaries represent portions of the home fragrance dispenser that form no part of the claimed design. The stippling in FIG. 8 indicates a portion of the home fragrance dispenser that illuminates in the illuminated state thereof.
